UNITED STATES PATENT OFFICE.

WILLIAM F. DUNLOP, OF NEW YORK, N. Y.

VAPOR OR GAS GENERATING APPARATUS.

1,099,848.

Specification of Letters Patent.

Patented June 9, 1914.

Application filed October 25, 1913. Serial No. 797,293.

To all whom it may concern:

Be it known that I, WILLIAM F. DUNLOP, a citizen of the United States, residing at New York, in the county of New York and 5 State of New York, have invented new and useful Improvements in Vapor or Gas Generating Apparatus, of which the following is a specification.

This invention relates to an apparatus for 10 generating medicinal gases or vapors for use in the treatment of pyorrhea, ulcerations and other like pus-produced and pus-producing diseases of the gums, teeth and other portions of the body, the object of the 15 invention being to provide an apparatus whereby a medicinal gas or vapor of a certain character may be produced and applied directly to the diseased surface so as to remove all pus, poisonous or irritating 20 accumulations and render the diseased parts aseptic, so as to effect a cure without danger of injury to the surrounding tissues.

The invention consists of the features of construction combination and arrangement 25 of parts herein described and claimed, reference being had to the accompanying drawing in which:—

Figure 1 is a side elevation of a gas or vapor generating apparatus constructed in 30 accordance with my invention. Fig. 2 is a vertical longitudinal section of the same. Fig. 3 is a top plan view of the apparatus. Fig. 4 is a detail vertical section on an enlarged scale, through the vapor storage tank 35 or chamber and the lower end of the medicament feed-pipe. Fig. 5 is a detail horizontal transverse section on the line 4—4 of Fig. 2.

In carrying my invention into practice, I 40 provide a tank 1 for containing oxygen, air or other suitable gas under a determined pressure, an oxygen compound of a character devised by me being preferably used. This tank is closed at its top by a head 2, 45 having threaded openings 3 and 4. Into the opening 3 is fitted a nipple 5 communicating with the lower end of a valve casing 6 having at one side an inlet pipe or passage 7. This pipe or passage 7 terminates 50 in a clamping yoke 8 whereby it may be connected to a primary tank containing the oxygen or oxygen compound gas, for replenishing the tank 1 therefrom whenever required. The casing 6 is provided with a 55 tapered valve chamber 9 in which is fitted a tapered plug valve 10 provided with a con-

trolling handle 11. The upper end of the casing is threaded to receive a gland or adjusting nut 12, arranged to bear upon a suitable packing or gasket 13, whereby a 60 gas tight connection is secured, the construction also being such that as the valve wears from continued use the nut may be tightened against the packing to force the valve down into its seat, thus maintaining a gas 65 tight connection.

Arranged within the tank 1 is a vapor storage and mixing tank 14 having a concaved bottom or mixing surface 15. This tank is threaded at its upper end in the 70 opening 4 of the head 2 and is supported by said head in a pendent position within the tank 1. Suitably secured to the top of the tank 14 is a nipple 16 provided with a passage 17 in communication with said tank, 75 which nipple has detachably coupled thereto a conductor 18 arranged in transverse alinement with the valve casing 6. Through this conductor extends a medicament feed passage 19 communicating at its upper end 80 with a cup or receptacle 20 normally closed by a screw cap or suitable closure member 21. The lower end of the passage 19 communicates with a delivery pipe or tube 22 which extends downwardly into the tank 14 85 and has its lower end arranged to bear against the center of the concaved bottom 15, the said lower end of the pipe 22 being provided with an annular series of jet apertures 23, for a purpose hereinafter described.

The valve casing 6 is provided at one side with a feed port 24 communicating with the pipe 7 and at its diametrically opposite side with a feed port 25. The 95 port 25 communicates with a pressure regulating or reducing valve 26, connecting said port 25 with a gas feed passage 27 formed in the conductor 18. A gas delivery pipe 28 communicates at its upper end with 100 the passage 27 and leads at its lower end into the pipe 22 a distance above the apertured lower end of the latter. The valve 10 has three positions, in one of which it opens communication between the pipe 7 and tank 105 1 for replenishing said tank with gas, in the second of which it opens communication between the tank 1 and passage 27 for the flow of gas from said tank 1 to the delivery pipe 28, in which position it cuts off communication between the tank 1 and pipe 7, 110 and a third or blank position in which the

ports 24 and 25 are closed and the valve therefore entirely cuts off communication between the tank 1 and the pipe 7 and also between said tank and the passage 27. In 5 the conductor 18 is formed a third passage 29, constituting a final vapor or gas discharge passage, with which connects one end of a hose or discharge pipe 30. Through this hose or discharge pipe the 10 generated vapor or gas is supplied to the part to be treated. To this end the free end of the hose is provided with a hand piece 31 terminating in a discharge nozzle 32 and into which may be detachably fitted 15 a discharge needle 33 of a restricted diameter, or of a diameter less than the discharge aperture or passage in the said discharge nozzle.

A gage 34 communicates with the tank 1, 20 so that the pressure of the primary gas or gas compound contained therein may be determined at any time, while a second gage 35 communicates either with the casing of the reducing valve 26 or at some suitable point 25 of the apparatus in communication with the interior of the tank 14, whereby the pressure of the generated vapor or gas therein may be determined.

In practice, the tank 1 is supplied with 30 oxygen or a compound oxygen gas to a desired pressure, which gas is stored therein for use as required, and when it is desired to employ the apparatus for the production of the medicinal gas or vapor a charge of 35 the medicament to be combined with the oxygen gas or oxygen gas compound is introduced into the cup or receptacle 20, whence it feeds by gravity downward through the passage 19 and pipe 22. Upon 40 the introduction of the medicament the valve 10 is turned to open communication between the tank 1 and passage 27, to admit the oxygen or oxygen compound gas under a determined pressure into the pipe 45 28. The gas flowing downward through said pipe enters the pipe 22 at a point above the jet orifices 23 and commingles with the liquid medicament, which is of a semi-volatile nature, and discharges the medicament 50 under pressure through the jet orifices 23 and against the concaved bottom or mixing surface 15 of the tank 14, whereby the medicament is thoroughly volatilized and commingled with the oxygen or oxygen gas compound, 55 forming a medicated vapor of a certain character which is stored within the chamber 14. This vapor discharges through the tube 30 and nozzle 31, by which it may be directed against or into the affected part 60 to be treated. Under a determined pressure of the oxygen or oxygen gas compound, which may be regulated by means of the valve 26, and in the use of the discharge tube without the needle 33, the medicament 65 may be injected in the vaporized condition

in which it exists in the storage tank 14, allowing it to be used in such condition against the affected surface. The medicated vapor is, however, of such a nature that by applying a needle 33 having a passage which 70 is of constricted size relative to the passage in the nozzle 32, a resistance to the outflow of the vapor will be created, establishing a certain additional pressure, under which the vapor is converted into a clear dry gas 75 which under some conditions of treatment is directed against or into the part to be treated. The needle not only enables this change in the conversion of the medicated vapor into a medicated gas without varying 80 the pressure through the reducing valve, but also enables the gas to be injected into cavities or pockets so as to directly reach the seat of the disease.

The apparatus is especially designed for 85 the production of a medicated gas or vapor for use in the treatment of pyorrhea and other purulent diseases, the gas or vapor being preferably produced from an oxygen compound formed of pure oxygen combined 90 with tissue stimulating agents, preferably alcohol, and oil of peppermint, and a medicament consisting of an aqueous solution of boracic acid, alcohol and oil of peppermint, the vapor or gas thus being saturated with 95 a local antiseptic and certain elements which are precipitated and act upon the tissues to stimulate the nerves and to induce an increased flow of blood to the part, thus providing for the absorption by the blood of an 100 increased amount of oxygen without danger of oxidation of the tissues, and at the same time stimulating the diseased parts so as to assist nature to a great degree in effecting a cure. The alcohol and menthol 105 contained in the oil of peppermint penetrate the tissues to an appreciable extent, thus allowing the oxygen to come into contact with the diseased cells and to act as a germicide in destroying all diseased matter 110 and germ life and neutralizing the pus, placing the tissues in an aseptic condition for a healing action.

It will be observed that the apparatus, 115 which is preferably of a portable character, provides for an efficient combination of the substances named and under a proper pressure to effect the volatilization of the ethylborate solution, and that the discharge of the remedial agent either in vaporous or 120 gaseous form may be readily and conveniently controlled by the operator.

I claim:

1. A vapor or gas producing apparatus comprising a gas containing tank, a mixing chamber having a medicament feed passage, a mixing surface, an inlet and a discharge outlet, a medicament feed pipe communicating with said medicament, and extending into said mixing chamber, said pipe having 125 130

- a delivery end in proximity to said mixing surface, a valved control connection between the gas receiving tank and said inlet, and a gas conducting connection leading from said 5 inlet to said medicament feed pipe and communicating with the latter adjacent its delivery end.
2. A gas or vapor generating apparatus comprising a gas receiving tank, a mixing 10 chamber having a gas inlet, a discharge outlet and a medicament passage, a medicament feed pipe communicating with said passage and having a delivery end provided with constricted outlets arranged in combination 15 with a wall of the chamber to effect a commingling of the gas and medicament to provide a medicated gas or vapor, a valve controlled connection between the gas receiving tank and the inlet, and a gas conducting connection 20 between said inlet and the medicament feed pipe communicating with the latter at a point adjacent to the delivery end thereof.
3. A gas or vapor generating apparatus 25 comprising a gas receiving tank, a mixing chamber having a concaved wall, and provided with an inlet, an outlet and a medicament feed passage, a medicament feed pipe communicating with said passage and 30 having a delivery end provided with jet apertures arranged in proximity to said concaved wall, a valve controlled connection between the gas receiving tank and the inlet, and a conducting connection between said 35 inlet and the medicament feed pipe communicating with the latter adjacent to the apertured end thereof.
4. A gas or vapor generating apparatus 40 comprising a gas receiving tank, a mixing chamber, a valve casing having inlet and outlet passages and a combined inlet and outlet passage communicating with the tank,
- and a valve in said casing controlling communication between said passages, an element connected with the chamber and having a medicament passage and inlet and outlet passages, the last-named communicating with the chamber, a connection between the outlet passage of the valve chamber and the inlet passage of said member, a medicament feed pipe communicating with the medicament passage and extending into the chamber and having an apertured delivery end, and a conducting pipe communicating with the inlet to said member and communicating with the medicament feed pipe adjacent the apertured end thereof. 45
5. A vapor or gas generating apparatus comprising a gas storage tank, a mixing tank, a valve casing having a passage communicating with the tank and inlet and outlet ports, a valve in said casing controlling communication between said passage and ports, a conductor having an outlet communicating with the mixing chamber and provided with an inlet and a medicament passage, a connection between the said inlet passage and the outlet passage of the valve casing, said connection having a pressure controlling valve therein, a medicament feed pipe communicating with the medicament passage and extending into the mixing chamber and having an apertured end terminating adjacent the bottom of said chamber, and a conducting pipe leading from the inlet of said conducting member and communicating with the medicament feed pipe adjacent the apertured end thereof. 50
6. A vapor or gas generating apparatus comprising a gas storage tank, a mixing tank, a valve casing having a passage communicating with the tank and inlet and outlet ports, a valve in said casing controlling communication between said passage and ports, a conductor having an outlet communicating with the mixing chamber and provided with an inlet and a medicament passage, a connection between the said inlet passage and the outlet passage of the valve casing, said connection having a pressure controlling valve therein, a medicament feed pipe communicating with the medicament passage and extending into the mixing chamber and having an apertured end terminating adjacent the bottom of said chamber, and a conducting pipe leading from the inlet of said conducting member and communicating with the medicament feed pipe adjacent the apertured end thereof. 55
7. A vapor or gas generating apparatus comprising a gas storage tank, a mixing tank, a valve casing having a passage communicating with the tank and inlet and outlet ports, a valve in said casing controlling communication between said passage and ports, a conductor having an outlet communicating with the mixing chamber and provided with an inlet and a medicament passage, a connection between the said inlet passage and the outlet passage of the valve casing, said connection having a pressure controlling valve therein, a medicament feed pipe communicating with the medicament passage and extending into the mixing chamber and having an apertured end terminating adjacent the bottom of said chamber, and a conducting pipe leading from the inlet of said conducting member and communicating with the medicament feed pipe adjacent the apertured end thereof. 60
8. A vapor or gas generating apparatus comprising a gas storage tank, a mixing tank, a valve casing having a passage communicating with the tank and inlet and outlet ports, a valve in said casing controlling communication between said passage and ports, a conductor having an outlet communicating with the mixing chamber and provided with an inlet and a medicament passage, a connection between the said inlet passage and the outlet passage of the valve casing, said connection having a pressure controlling valve therein, a medicament feed pipe communicating with the medicament passage and extending into the mixing chamber and having an apertured end terminating adjacent the bottom of said chamber, and a conducting pipe leading from the inlet of said conducting member and communicating with the medicament feed pipe adjacent the apertured end thereof. 65
9. A vapor or gas generating apparatus comprising a gas storage tank, a mixing tank, a valve casing having a passage communicating with the tank and inlet and outlet ports, a valve in said casing controlling communication between said passage and ports, a conductor having an outlet communicating with the mixing chamber and provided with an inlet and a medicament passage, a connection between the said inlet passage and the outlet passage of the valve casing, said connection having a pressure controlling valve therein, a medicament feed pipe communicating with the medicament passage and extending into the mixing chamber and having an apertured end terminating adjacent the bottom of said chamber, and a conducting pipe leading from the inlet of said conducting member and communicating with the medicament feed pipe adjacent the apertured end thereof. 70
10. A vapor or gas generating apparatus comprising a gas storage tank, a mixing tank, a valve casing having a passage communicating with the tank and inlet and outlet ports, a valve in said casing controlling communication between said passage and ports, a conductor having an outlet communicating with the mixing chamber and provided with an inlet and a medicament passage, a connection between the said inlet passage and the outlet passage of the valve casing, said connection having a pressure controlling valve therein, a medicament feed pipe communicating with the medicament passage and extending into the mixing chamber and having an apertured end terminating adjacent the bottom of said chamber, and a conducting pipe leading from the inlet of said conducting member and communicating with the medicament feed pipe adjacent the apertured end thereof. 75

In testimony whereof I affix my signature in presence of two witnesses.

WILLIAM F. DUNLOP.
